UNITED STATES PATENT OFFICE.

THOMAS F. MORRIN, OF JERSEY CITY, NEW JERSEY, ASSIGNOR TO
ELIZABETH T. MORRIN, OF SAME PLACE.

STEAM-GENERATOR.

SPECIFICATION forming part of Letters Patent No. 664,358, dated December 18, 1900.

Application filed November 29, 1899. Serial No. 738,643. (No model.)

To all whom it may concern:

Be it known that I, THOMAS F. MORRIN, a citizen of the United States, residing at Jersey City, Hudson county, State of New Jersey, have invented certain new and useful Improvements in Steam-Generators, of which the following is a specification.

My invention relates to steam-generators, and has for its object to produce a generator capable of rapidly and economically generating steam.

In the accompanying drawings I have shown a steam-generator embodying my invention. These drawings are, however, illustrative merely, and my invention is not necessarily limited to the generator shown.

In the drawings, Figure 1 is a transverse vertical section of the generator on line I I of Fig. 3. Fig. 2 is a detail sectional view showing the arrangement of one of the baffle-plates with reference to the tubes. Fig. 3 is an elevation of the generator in half-section, and Fig. 4 is an enlarged detail view of the lower manifold-chamber.

In the drawings, *a* represents the casing of the generator, and *b* the fire-bed or fire-box, herein shown as an ordinary grate. The tubes *c c* are arranged in two inclined sets, one set communicating at its lower end with the lower manifold-chamber *d*, and the other set of tubes communicating at its lower end with the upper manifold-chamber *e*. Both sets of tubes are inserted in the tube-sheet *f'* of the uppermost manifold-chamber *f* or steam-drum. This tube-sheet *f'* is of a thickness corresponding to the thickness of a boiler-shell having the same radius as the tube-sheet. The tube-sheets *d'* and *e'* of the manifold-chambers *d* *e*, into which the lower ends

of the tubes enter, are parallel to the parts of the tube-sheet *f'* which are opposite to them, (or substantially so,) being preferably curved on the same radius as the tube-sheet *f'* and preferably of the same thickness as the said tube-sheet. Pipes *g* connect the steam-drum or manifold-chamber *f* with the manifold-chambers *d* and *e*, and inclined pipes *h* (only one of which is shown in any one figure) connect the manifold-chambers *d* and *e* with each other.

At about the middle of each set of tubes I provide an inclined baffle-plate *i* to direct the flame and products of combustion. The baffle-plates are not quite as wide as the set of tubes and have free spaces between their outer edges and the outermost rows of tubes.

In each set of tubes I have shown tubes *c'*, which are larger than the tubes *c* and aid in maintaining the circulation. The tubes *c* are also shown as arranged in pairs of rows, with a passage between each pair of rows, along which a wounded tube may be removed from the generator without disturbing the others.

When the tubes *c'* are used, the side circulation-tubes *g* may be dispensed with.

Having described my invention, what I claim, and desire to secure by Letters Patent, is—

1. In a steam-generator, in combination, the steam-drum *f'*, the manifold-chambers *d* *e*, the sets of inclined tubes *c c* connecting the drum and manifold-chambers and the baffle-plates *i* located among the sets of tubes and leaving a free open space between the outermost row of tubes and the side edges of the baffle-plates, as set forth.

2. In a water-tube boiler, the combination of two headers or manifold-chambers, a series of parallel water-tubes uniting the headers or manifold-chambers, and a series of tubes *c'* parallel with and of larger size than the other tubes set in the structure at or near one side of the group or series of tubes.

3. In a water-tube boiler, the combination of a group or set of inclined water-tubes, tube-sheets which the water-tubes enter, and a baffle-plate located among the tubes and extending from end to end thereof and leaving a free space between the outermost tubes and the free edges of the baffle-plate.

4. In a water-tube boiler, the combination of a steam-drum, a plurality of manifold-chambers, and a plurality of groups of inclined water-tubes connecting the steam-drum to the manifold-chambers, one of the said groups of tubes being shorter than the other and a fire bed or grate *b* located in the space between the two groups of tubes and a fire door or opening located below the mani-

fold-chamber of the shorter group of tubes and constituting a means of access to the fire-bed.

5. In a water-tube boiler, the combination of a steam-drum *f* having a convexly-curved tube-sheet *f'*, a plurality of headers of a general meniscus form in cross-section located some distance apart and having concavely-curved tube-sheets *d' e'* substantially parallel with the tube-sheet *f'* and groups of water-tubes of substantially the same effective length uniting the steam-drum and headers and set in the tube-sheets thereof.
10. In a boiler, the combination of an upper

steam-drum, a manifold located at front of 15 the fire-bed and a manifold located at the rear of the fire-bed, a set of inclined groups of water-tubes connecting each manifold with the steam-drum, inclined pipes *h*, one at each end of the manifolds, connecting the said 20 manifolds, and inclined pipes *g g* at each end of the manifolds, connecting the manifolds with the steam-drum.

THOMAS F. MORRIN.
